(57) **CLAIM**

The ornamental design for a floor attachment, as shown and described.

DESCRIPTION

FIG. 1 is a top, front, right side perspective view of a floor attachment showing my new design;

FIG. 2 is a front elevation view thereof;

FIG. 3 is a rear elevation view thereof;

FIG. 4 is an enlarged left side elevation view thereof;

FIG. 5 is an enlarged right side elevation view thereof;

FIG. 6 is a top plan view thereof; and,

FIG. 7 is a bottom plan view thereof.

The broken lines in the drawings illustrate portions of the floor attachment that form no part of the claimed design.

1 Claim, 6 Drawing Sheets
